UNITED STATES PATENT OFFICE.

PAUL S. MABLE, OF JANEVILLE, WISCONSIN.

DIRT SEPARATOR.

Application filed April 11, 1924. Serial No. 705,793.

This invention relates to dirt or dust separators, and particularly to separators of the type which are used to purify the air supplied to the intake manifold of gas engines.

5 The object of the invention is to provide a dust separator or air purifier which will be cheap to manufacture, durable in construction, small in size, and efficient in operation.

10 It is believed the invention will be understood most readily from a detailed description thereof taken in connection with the accompanying drawings, in which—

15 Figure 1 is a plan view of one form of applicant's invention;

Figure 2 is a vertical section substantially through the line 2—2 of Figure 1;

Figure 3 is a side view of a modified form of applicant's separator;

20 Figure 4 is a section substantially on the line 4—4 of Figure 3, and

Figure 5 is a section on the line 5—5 of Figure 4.

25 Referring now to the drawings, in which like reference characters indicate the same parts in the several views, 10 schematically indicates a carburetor, the intake 11 of which is joined through the medium of the pipe 12 to the upwardly extending outlet 13 of applicant's dirt separator. The separator consists of the substantially thimble-shaped member 14 having the outwardly directed flange 15 which forms an upper circular deflecting baffle. The member 14 adjacent to

30 the upper end thereof is screw threaded and has attached thereto the upper substantially semi-spherical half 16 of the separator housing. The housing member 16 is provided with a laterally extending tube 17 which is arranged adjacent to the circumference thereof and directed tangentially thereto. The member 16 adjacent to the lower edge thereof is provided with the outwardly directed flange 18. The bottom portion of the

35 casing is provided by the downwardly tapered member 19 which has at its upper edge the laterally directed flange 20 secured to the flange 18 by means of the bolts 21. The casing or housing member 19 is provided at the lower end thereof with an opening 22, and has at the lower end thereof the laterally directed baffle plates 23 which extend downwardly into the opening 22.

40 Secured to the lower end of the member 14, by means of the cap screw 24, is the curved or concaved member 25 which forms

a lower shield or circular baffle member, the upper edge of which terminates adjacent to the lower surface of the outwardly directed flange or baffle 15 but a substantial distance within the outer edge thereof. The member 14 is provided between the flange 15 and the shield member 25 with a plurality of air inlet openings 26 through which the air passes to the inside of the member 14. 65 The outer end of the air intake tube or conduit 17 is provided with a shield 27 secured in position in any desired manner, as by the brackets 28 and screws 29.

70 The operation of the device is as follows:

The air entering the carburetor 10 is drawn in through the intake conduit 17 to the space 30 between the upper casing members 16 and the flange 15. The air then passes downwardly through the narrow 75 opening 31 at the outer edge of the flange 15 into the space within the lower casing member 19. As the space 31 is relatively narrow, the air with the entrained dust passes downwardly therethrough very rapidly, and 80 the dust and heavier particles within the air continue on their downward course to the bottom of the member 19 and out through the opening 22. Due to the baffle plates 23 arranged adjacent to the opening 22, the air 85 adjacent to the opening is prevented from a rotary or swirling motion, and the dirt readily passes from the separator casing. The air, however, which is drawn downwardly through the space 31 passes through 90 the space 32 within the shield member 25, through the openings 26 to the inside of the member 14. A large portion of the air entering through the conduit 17 is drawn to the opposite side of the separator, and in moving 95 around the member 14 in the space 30, it causes a centrifugal action to be exerted on the dirt and grit particles in the air which causes them to be impelled against the casing member 16 and downwardly through the 100 space 31. The air, which moves rapidly while passing downwardly thru the space 31 causes the grit and dirt particles to have such a momentum that they do not follow the air in its relatively slow return 105 movement to the opening 32.

Figures 3, 4 and 5 show a modified form of applicant's invention. The device shown in Figures 1 and 2 is designed to have the air exit opening extend upwardly, whereas 110 the device of Figures 3, 4 and 5 is arranged to have the air exit opening extend down-

55

wardly. The device of Figures 3, 4 and 5 consists of but two castings. The upper casting 35 is inverted bowl shape in contour and is provided with the laterally directed intake conduit 36 which is arranged adjacent to the outer edge of the member 35 and directed tangentially thereto.

Within the bowl shaped member 35 is the air outlet member 37, the upper end of which 10 is secured to the member 35 by means of the cap screw 38. The member 37 is generally cylindrical in contour and has the outwardly extending flange 39, the edge of which is spaced slightly from the lower edge of 15 the member 35 to provide the narrow opening 40. The member 39 is provided with a plurality of spaced downwardly extending wings or baffle plates 41 which engage the member 35 adjacent to the lower edge thereof. 20 The member 37 is provided at one side thereof with the laterally extending enlargement 42 which substantially fills the space between the member 37 and the member 35 at one side thereof. The enlargement 42 terminates short of member 35 to provide a passage 25 47 the purpose of which will later appear. The member 42 is provided in the side remote from the conduit 36 with an opening 43 through which air may enter the member 30 37 of the separator.

The outer end of the conduit 36 is provided with the shield 44 which is shown as secured thereto by means of the bracket members 45 and screws 46. The shield 44 35 of the modification of Figures 3 to 5, and the shield 27 of the form shown in Figure 1 acts to deflect the heavier particles of grit and dirt from the separator. This expedient, however, is old and forms no part of the 40 present invention.

The operation of the device shown in Figures 3 to 5 is as follows:

Air passing to the carburetor through the member 37 is drawn in through the conduit 36, passes centrifugally around the space 47 between the central member 37 and the cover 35, through the opening 43 to the inside of the member 37. Due to the fact that the air entering the member 37 has to pass nearly 50 around the member 37 before reaching the opening 43, the grit and heavier particles entrained in the air are thrown by centrifugal force against the lateral wall of the member 35 and pass downwardly through 55 the opening 40. The baffle plates 41 adjacent to the opening 40 prevent the centrifugal movement of the air at this point and greatly facilitate the passage of the grit and dirt particles from the separator. Certain of the 60 particles entrained in the air may not have passed out through the opening 40 by the time the air has reached the intake 43. Such particles will, however, have been thrown outwardly against the casing 35 by 65 the centrifugal action and will, therefore,

pass through the space 47 provided at the outer edge of the extension 42 and will eventually find its way out through the opening 40.

While in the drawings and the above description applicant's invention has been limited to certain definite details of construction, it is to be understood that various modifications are contemplated, and the invention should, therefore, be limited merely by the scope of the appended claims.

Having thus described my invention, what I claim as new and desire to secure by Letters Patent of the United States is:

1. In a dirt separator for internal combustion engines, a casing forming a centrifugal whirling chamber, an air inlet entering the upper part of said whirling chamber tangentially to impart a centrifugal whirling motion to the air entering said chamber, the lower portion of said chamber being of conical formation converging to a lower dust outlet, a plurality of plates adjacent said outlet and extending upwardly along the inner conical surface of said chamber, 80 a pair of baffles supported in superposed relation in said chamber between said air inlet and said dust outlet, the lower baffle having its peripheral edge disposed in close proximity to the under side of the upper baffle whereby air entering the space between said baffles is drawn between said baffles in a relatively thin curtain, and an air outlet from said chamber having its inlet terminating in the area between said 90 baffles.

2. In a dust separator for internal combustion engines, the combination of the casing forming a centrifugal whirling chamber and comprising an upper casing section and 100 a lower casing section of conical form, a tangential air inlet entering said upper casing section, a pair of baffle plates extending across said chamber, a dust outlet at the bottom of said conical casing section, and deflecting plates positioned adjacent said dust outlet and extending upwardly across the bottom portion of said conical section and along the side of said casing.

3. In a dirt separator for internal combustion engines, a casing forming a centrifugal whirling chamber, an air inlet entering the upper part of said whirling chamber tangentially to impart a centrifugal whirling motion to the air entering said chamber, a dust outlet leading from the lower part of said chamber, a pair of circular baffles supported in superposed relation in said chamber between said air inlet and said dust outlet, an air outlet leading 110 axially from said chamber and drawing air solely from the area between said two baffles, one of said baffles being bowl-shaped, the lower baffle having its peripheral edge disposed in close proximity to the under side 120 125

- of the upper baffle, whereby the air entering said air outlet is first drawn between said baffles in a relatively thin curtain.
4. In a dust separator for internal combustion engines, a casing forming a centrifugal whirling chamber, an air inlet entering said whirling chamber tangentially to impart a centrifugal whirling motion to the air in said chamber, an upper circular baffle extending transversely across the whirling chamber with its periphery terminating adjacent the wall of said chamber, the air entering said whirling chamber from said air inlet being caused to pass down through the annular opening between said upper baffle and the wall of said chamber, the lower portion of said chamber being of conical formation converging to a lower dust outlet, a plurality of plates adjacent said outlet and extending upwardly along the inside of said chamber, a circular lower baffle disposed below said upper baffle, and an air outlet drawing from the region between said baffles, said lower baffle being disposed in close proximity to said upper baffle to cause the air entering said air outlet to flow in a relatively thin curtain inwardly along the under side of said upper baffle.
5. In a dust separator for internal combustion engines, a casing of turnip-shape comprising an upper casing section and a lower casing section of conical form, means for joining said casing sections together, a tangential air inlet entering said upper cas-
- ing section, a dust outlet leading from the bottom of said conical lower section, a thimble member carried by said upper section and extending down into the whirling chamber axially thereof, a circular baffle carried by said thimble member and having its periphery terminating in close proximity to the inner wall of said whirling chamber, a second baffle below said first named baffle, a screw for mounting said second baffle on the bottom of said thimble member, and a plurality of air inlets to said thimble member between said baffles.
6. In a dust separator for internal combustion engines, a casing forming a centrifugal whirling chamber and comprising an upper casing section and a lower casing section of conical form, a tangential air inlet entering said upper casing section, a dust outlet leading from the bottom of said lower casing section, a separate tubular member carried by said upper casing section and extending into said whirling chamber axially thereof, a circular baffle extending from said tubular member transversely of said whirling chamber and its periphery lying in close proximity thereto, and a bowl-shaped baffle supported on said tubular member below said first named baffle, said tubular member constituting an air outlet and drawing its air from the region between said baffles.

In witness whereof, I hereunto subscribe my name this 1 day of April, 1924.

PAUL S. MABIE.
